UNITED STATES PATENT OFFICE.

MACK BLATT, OF DETROIT, MICHIGAN, ASSIGNOR TO EDGAR P. BOWMAN, OF DETROIT, MICHIGAN.

DESIGN FOR A VACUUM-CLEANER NOZZLE.

Application filed March 30, 1927. Serial No. 21,401. Term of patent 3½ years.

To all whom it may concern:

Be it known that I, MACK BLATT, a citizen of the United States, residing at Detroit, in the county of Wayne and State of Michigan, have invented a new, original, and ornamental Design for a Vacuum-Cleaner Nozzle, of which the following is a specification, reference being had to the accompanying drawing, forming a part hereof, and in which—

Fig. 1 is a side elevational view of the invention.

Fig. 2 is a top plan view of the invention.

Fig. 3 is a bottom plan view of the invention.

Fig. 4 is a front elevational view.

What I claim is:

The ornamental design for a vacuum cleaner nozzle, as shown.

MACK BLATT.
